UNITED STATES PATENT OFFICE.

HENRY P. MALONEY, OF ST. LOUIS, MISSOURI, ASSIGNOR OF ONE-HALF TO HARRY HARRIS, OF ST. LOUIS, MISSOURI.

MANIFOLD LOCK FOR INTERNAL-COMBUSTION ENGINES.

1,426,308.

Specification of Letters Patent. Patented Aug. 15, 1922.

Application filed February 8, 1919. Serial No. 275,729.

To all whom it may concern:

Be it known that I, HENRY P. MALONEY, a citizen of the United States, and resident of the city of St. Louis and State of Missouri, have invented certain new and useful Improvements in Manifold Locks for Internal-Combustion Engines, of which the following is a specification containing a full, clear, and exact description, references being had to accompanying drawings, forming a part thereof.

My invention relates to certain new and useful improvements in manifold locks and has for its primary object a locking device which is interposed between the carbureter and the intake manifold of an internal combustion engine.

Another object is to provide a locking device for the intake manifold of an internal combustion engine which is operated from the dash or instrument board of an automobile, and which may be securely locked by means of a key so as to prevent the unauthorized use of the machine.

In the drawings:

Fig. 1 is a view of an automobile showing engine, instrument board, carbureter, intake manifold and my improved device in operative position.

Fig. 2 is an enlarged longitudinal sectional view of the lock and its connecting parts taken on the line 2—2 of Fig. 3.

Fig. 3 is a plan view of the device taken on the line 3—3 of Fig. 2.

Fig. 4 is a sectional view taken on the line 4—4 of Fig. 2.

Fig. 5 is a sectional view taken on the line 5—5 of Fig. 2, and

Fig. 6 is a sectional view taken on the line 6—6 of Fig. 2.

Referring to the drawings, 7 indicates the instrument board of an automobile, motor boat, or in fact, any internal combustion engine on which the different instruments for operating and controlling the same are located.

8 indicates an internal combustion engine which is of any well known construction. 9 indicates the carbureter and 10 the intake manifold. Between the carbureter 9 and the manifold 10 is interposed my improved lock valve 11, this lock being operated by a flexible shaft 12 which is located in a flexible tube 13, this tube being preferably composed of some hardened material such

as steel or the like, so that the same cannot readily be cut and access had to the flexible shaft 12.

One end of the flexible tube 13 is connected to a sleeve 14 by means of a coupling 15. The sleeve 14 extends through the instrument board 7 and is provided with an integral flange 16 through which openings 17 are formed. The sleeve 14 and flange 16 are further provided with an additional cylindrical flange 18 in which a plurality of openings 19 are formed. These openings 19 are radially disposed as fully shown in Fig. 6. The purpose of these openings will be explained in detail later.

Within the sleeve 14 is located a knob 20 which is provided with a shank 21 and to this shank 21 is attached the end 22 of the flexible shaft 12. In the knob 20 is located the barrel of a lock which is indicated by the numeral 23. This barrel is partially rotatable so that after the key has been inserted, the pins 25 can be withdrawn from engagement with the openings 19 formed in the flange. This barrel is provided with the usual key opening so that an ordinary key of the cylinder lock type may be inserted.

To the end of the key barrel 23 are pivotally attached levers 24, these levers in turn being attached to pins 25 which are actuated by springs 26, these pins and springs being located in the hollow portion 27 which is formed immediately back of the knob 20. The pins 25 extend into the openings 19 and are for the purpose of holding the knob and shaft 12 against rotation when the key is removed. The outside of the sleeve 18 is covered by a second sleeve, so that the openings 19 are closed from the outside and there will be no possibility of any instrument or instruments being inserted and effect a picking of the lock and the release of the manifold lock.

The opposite end of the shaft 12 is attached to a shank 28 on the end of which is located a pinion 29, this pinion meshing with teeth 30 formed on the diaphragm or shutter 31 which is mounted in the lock 11.

The lock 11 is constructed of several sheets of hardened steel 32, 33, 34, 35 and 36. These members or plates are all shaped as indicated in Fig. 3 and have bolt openings 37 by means of which the lock is secured between the carbureter and the intake mani-

fold. These plates are also provided with a series of bolt openings 38 through which the bolts 39 project, these bolts 39 securing the several plates together with the exception of 5 plate 36 which plate acts as a cover or protector for the heads of the bolts 39.

The plate 34 is provided with a sleeve 40 which projects through an opening 41 formed in the plate 36. This sleeve 40 is provided 10 with a bore 42 in which a sleeve 43 is inserted, this sleeve acting as a bearing for the shank 28 formed on the pinion 29. The free end 44 of the sleeve 40 is counterbored as indicated by the numeral 45 and receives the 15 end 46 of the flexible tubing 13. The end 47 of the flexible shaft 12 is secured to the shank 28 in any well known manner so that the shank and pinion may be rotated.

The plates 33, 34 and 35 are provided with 20 a partial bore 48 in which the pinion 29 is seated, the plate 32 preventing any access being had to the pinion 29 and also covering the partial bore 48 formed in the other plates. The plate 32 is provided with a pair 25 of grooves 49 extending on either side of the opening 50 leaving a central portion or rib 51, which acts as a guide for the diaphragm 31, this diaphragm being recessed along its central portion as indicated by the numeral 30 52 so as to fit over the tongue or rib 51 formed on the member 32. The plates 33 and 34 are merely filling in plates to take care of the thickness of the diaphragm or 35 shutter and are to prevent any lateral movement, that is, to allow a free up and down movement, so that the opening between the carburetor and the intake manifold can be closed but still hold this diaphragm or shutter from vibrating and allowing gas leakage.

40 The lock member 11 is so constructed or rather made of different sizes, so that the same can be applied to any make of machine but the essential or main features, that is the diaphragm 31, the lock mechanism and 45 the flexible shaft and flexible tubing, remain the same for all machines.

The operation of my device is as follows:

The diaphragm 31 being in position as shown in Fig. 3, the intake manifold is fully 50 opened and the pins 25 are seated in some pair of the openings 19. When it is desired to lock the machine, a key is inserted in the barrel 23 of the lock and by a quarter turn of the key, the pins 25 are withdrawn from 55 the openings 19 allowing the knob 20 to be rotated or turned. This rotation or turning is transmitted through the flexible shaft to the pinion 29 which, meshing with the teeth 30 of the diaphragm 31, will raise the same.

60 When the diaphragm is raised to its uppermost position, a certain amount of resistance can be felt upon the knob 20. The key 21 is then turned one quarter of a revolution backward and the knob continued to be

turned in the direction that it was before, 65 turning the barrel until the pins 25 click into another pair of the openings 19, thus securely holding the shutter in locked position and the knob, flexible shaft and pinion against rotation in either direction. The 70 key is then removed and no access can be had to the pins 25 for releasing the same without destroying the locking mechanism entirely, nor can the diaphragm 31 be 75 opened other than by the manipulation of the lock and knob located on the instrument board or by a great amount of work in cutting through the hardened flexible tubing 13 and the flexible shaft 12. When it is desired to again place the carburetor and intake manifold in operative condition, the 80 operation is repeated with this exception, that the knob 20 is rotated or turned in the opposite direction, thus lowering the diaphragm 31 and establishing communication 85 between the carburetor and intake manifold.

Having fully described my invention what I claim is:

1. A manifold lock for internal combustion engines comprising a sleeve, an annular 90 flange formed on one end thereof, a cylindrical flange formed on the annular flange and concentric with said sleeve, a shank rotatably mounted in said sleeve, a knob formed integral with said shank, a key operated barrel mounted in said knob, a pair of levers pivotally attached to said key barrel, spring actuated pins attached to the levers, 95 openings formed in the shank, said openings adapted to permit the passage of the pins 100 therethrough, a plurality of radially disposed openings formed in the cylindrical flange, said openings registering with the openings formed in the shank and adapted to permit the entrance of the pins to lock 105 the knob against rotation.

2. A manifold lock for internal combustion engines comprising a sleeve, a circular flange formed on one end thereof, a cylindrical flange concentric with the sleeve 110 formed at right angles to the circular flange, a shank adapted to be seated in said sleeve, a knob formed integral with the shank, a key operated barrel rotatably mounted in 115 said knob, a pair of spring actuated pins pivotally connected to said knob, said pins extending through the shank, a plurality of radially disposed openings formed in the cylindrical flange, said openings adapted to receive the spring actuated pins to lock the 120 knob against rotation.

In testimony whereof, I have signed my name to this specification in the presence of two subscribing witnesses.

HENRY P. MALONEY.
